HOLDER FOR FOOD BOWLS FOR PETS

Tony Robert, 5701 Southwest Freeway,
Houston, Tex. 77027

Filed Feb. 16, 1968, Ser. No. 10,608

Term of patent 14 years

U.S. Cl. D30—13
Int. Cl. D30—02

FIGURE 1 is a perspective view of the top, a side and an end of a holder for food bowls for pets, showing my new design;

The bowls shown in broken lines in FIG. 1 are depicted for purposes of illustration only.

I claim:

The ornamental design for a holder for food bowls for pets, as shown and described.
